UNITED STATES PATENT OFFICE

EINAR RØNNE, OF COPENHAGEN, DENMARK, ASSIGNOR TO F. L. SMITH & CO., OF NEW YORK, N. Y., A CORPORATION OF NEW JERSEY

ROTARY KILN

Application filed July 9, 1931, Serial No. 549,610, and in Great Britain August 25, 1930.

This invention relates to the burning in a rotary kiln of a material which is delivered to the kiln in the form of a slurry, such as raw slurry for the manufacture of hydraulic

5 cement.

Economy in the operation of rotary kilns has been accomplished heretofore by the suspension within the drying zone of the kiln of movable heat transmitting bodies, such 10 as chains, rings, network or the like, the transmission of heat from the combustion gases to the material to be burned being increased by these bodies. The provision of heat transmitting bodies in the drying zone 15 of a rotary kiln, however, in the burning of some kinds of materials, creates so much resistance to the passage of the material through the kiln tube as to reduce the output of the kiln.

20 It is the object of the present invention to overcome this disadvantage and to increase the effectiveness of the heat transmitting bodies.

In accordance with the invention, the kiln 25 is made up of two or more independently rotating tube sections and the drying is carried out wholly or partly in one of the sections which is furnished with heat transmitting bodies, such as chains, rings, network or 30 the like, and which is rotated at a higher speed than the other tube section or tubes in which the burning is carried out. In this manner the slurry-like material, which covers the surface of the heat transmitting bodies 35 in the form of a film, is brought into more intimate contact with the combustion gases from the burning zone and the transmission of heat is thereby increased. The rate of movement of the material through the drying zone is also increased and a higher output is secured.

The section which forms the burning zone and the independently rotating section which forms the drying zone may be arranged in alignment, one after the other, but the inclination of the axes of the tubes, as will be understood, may be varied according to the speed at which the material is to pass through the two parts of the kiln. The 45 drying section may also be arranged other-

wise with respect to the burning section with suitable provision for the conduction of the material and of the combustion gases from one to the other.

The slurry-like material may be introduced into the drying section in any usual or suitable manner and the drying section may have such shape and dimensions as will be best suited to the conditions of operation.

55 In the accompanying drawing, in which a 60 convenient embodiment of the invention is illustrated,

Figure 1 is a diagrammatic view, partly in elevation and partly in section, and

Figure 2 is a detail view in longitudinal 65 section showing particularly the connection between the two parts of the kiln.

The kiln shown comprises a part or section 1 which forms the burning zone and a part 70 or section 2 which forms the drying zone, the two sections being mounted in alignment with each other but arranged to rotate independently of one another. The drying zone is provided with heat transmitting bodies in the form of chains 3 and for the purpose of providing room for a large number 75 of such chains and for the passage of a large amount of material the upper part of this section is enlarged relatively to the rest of the section. The gases of combustion are drawn out through a smoke chamber 4 and the slurry is introduced through an inlet pipe 5.

80 The connection between the two sections 85 1 and 2 is preferably as shown in detail in Figure 2. The lower end of the drying section 2 extends telescopically into the upper end of the burning section 1, the latter being provided with helical ribs 6 and an internal flange 7 to prevent any material passing backward. The joint between the two sections 80 90 1 and 2 is surrounded by a casing 8 which is fixed to the lower section 1 to rotate therewith but can move relatively to the upper section 2. This casing is sealed with respect to the upper section 2 by an annular plate 10 which slips in a grooved member. If any material passes back from the section 1 through the joint, it is caught by the casing 100

8 and is returned into the section 1 by pipes 9 which run partly around the kiln in a direction opposite to that of the rotation of the kiln.

10 The section 1 may be rotated as usual, as by a gear ring 12 and gear 13, and the section 2 may be rotated similarly, but at a higher speed, as by a gear ring 14 and gear 15.

I claim as my invention:

11 1. A rotary cement burning kiln comprising independently rotatable sections in alignment and forming respectively a drying zone and a burning zone, means to rotate said sections independently of each other, a casing surrounding the joint between the sections, the casing being fixed to one of the sections and movable with respect to the other section, means to form a slip seal between the casing and said other section, and means to transfer material from the casing to the burning zone.

12 2. A rotary cement burning kiln comprising independently rotatable sections in alignment and forming respectively a drying zone and a burning zone, means to rotate said sections independently of each other, a casing surrounding the joint between the sections, and a pipe connected at one end with the chamber of the casing and at the other end into the burning zone, such pipe extending around the kiln in a direction opposite to that of the rotation of the kiln.

This specification signed this 22nd day of June, A. D. 1931.

CERTIFICATE OF CORRECTION.

Patent No. 1,914,462.

June 20, 1933.

EINAR RONNE.

It is hereby certified that the name of the assignee in the above numbered patent was erroneously described and specified as "F. L. Smith & Co." whereas said name should have been described and specified as "F. L. Smidth & Co." as shown by the records of assignments in this office; and that the said Letters Patent should be read with this correction therein that the same may conform to the record of the case in the Patent Office.

Signed and sealed this 29th day of August, A. D. 1933.

M. J. Moore.
